LOUNGE SEAT

Henry A. Wilson, 1001 Central, Miamisburg, Ohio
45342, and Elmer R. Long, Jr., 301 Ives Lane, Kettering,
Ohio 45429

Filed Feb. 9, 1972, Ser. No. 225,026

Term of patent 14 years

Int. Cl. D6—01

U.S. Cl. D6—37

FIG. 1 is a perspective view of a lounge seat showing our new design;

FIG. 2 is a right side elevational view;

FIG. 3 is a top plan view;

FIG. 4 is a front elevational view; and

FIG. 5 is a rear elevational view.

We claim:

The ornamental design for a lounge seat, substantially as shown and described.
